INVENTOR

UNITED STATES PATENT OFFICE.

ANTHONY MANGIANIELLO, OF WEST PITTSTON, PENNSYLVANIA.

PAVING CONSTRUCTION.

Application filed December 11, 1922. Serial No. 606,022.

To all whom it may concern:

Be it known that I, ANTHONY MANGIANIELLO, a citizen of the United States, and a resident of West Pittston, county of Luzerne, State of Pennsylvania, have invented 5 certain new and useful Improvements in Paving Constructions, of which the following is a specification, reference being had to the accompanying drawings.

10 My invention relates to improvements in the laying, replacement and repair of roadway pavements.

15 A principal object of my invention is to provide means to facilitate the laying, repair and replacement of block pavements particularly where the pavement is adjacent to and between street railway tracks.

20 A further object of my invention is to provide an improved pavement construction for use at street intersections and grade crossings where the re-building or re-laying of street railway or railroad tracks is frequently necessitated by reason of the wear to which the rails are subjected at such 25 points.

25 A further object of my invention is to provide a pavement construction which may be removed and replaced in a minimum amount of time whereby the inconvenience, 30 annoyance and obstruction to traffic is greatly reduced.

35 A further object of my invention is to provide a series of supports for the pavement blocks, the units of which are independently removable and interchangeable.

40 The invention further includes all of the other various objects and novel features of construction and arrangement hereinafter more definitely specified and described.

45 In the accompanying drawings, Fig. 1 is a fragmentary top plan view of one embodiment of my improvement; Fig. 2 is a transverse section taken on the line 2—2 of Fig. 1, the lifting device hereinafter referred to being also shown; Fig. 3 is a side elevation partly shown in section; Fig. 4 is a detail end elevation of a supporting plate or member used between the rails of a track; Fig. 5 is a side elevation of the plate or member 50 shown in Fig. 4; Fig. 6 is a transverse section on the line 6—6 of Fig. 4; Fig. 7 is a plan view of the lifting device and Fig. 8 is a side elevation, partially shown in section, of the lifting device.

55 Like numerals refer to like parts in the several figures.

Rails 1 and 2 are the usual rails of a street railway or a railroad track which rest upon the usual sleepers or ties 3. A supporting plate or member 4, which may preferably be cast from iron, is of a width slightly less than the width between the rails 1 and 2 and comprises a bottom 5 strengthened on its under side by ribs 6 which meet or intersect ribs 7 extending 60 transversely thereto the ends of which are cut away as at 9 so as to fit the bases of the rails 1 and 2. Ribs or flanges 10 slightly spaced from the side edges of the plates 4 extend upwardly therefrom to a height preferably of the thickness of the blocks 11 which form the pavement. In practice, I have found it desirable to spread a cushion of sand 12, say $\frac{1}{4}$ " in thickness, upon the 65 top of the plate 4 upon which the paving blocks may rest. Means at the ends of the plates 4 for assisting in retaining the sand are provided by the members 13 formed integrally with the plates, projecting upwardly therefrom slightly and joining at 70 their ends the ribs 10.

75 It is desirable and in many instances essential that the block pavement be installed outside of the rails, and I have provided new and useful means therefor consisting 80 of supporting members or plates 14, preferably metal castings, comprising a bottom 15, a depending flange 16 and side ribs or flanges 17 extending upwardly to a height 85 preferably of the thickness of the blocks 11. 90 Means 18 similar to members 13 are provided at the ends of plates 14, join at their ends the ribs 17 and assist in retaining the sand upon the plates 14. Within the flanges 16 are provided suitable holes for registry 95 with holes in the web 19 of the rails and through which are passed bolts 20 whereby the supporting members 14 are securely held in place. The length of the supporting plate 14 is preferably the same as that of the supporting member 4 so that when assembled their ends will be in alignment. The flange 16 extends along the web of the rail resting upon the base 21 thereof, and transverse strengthening ribs 22 depend 100 from the plates 14 being cut away at their inner ends as at 23 so as to fit the bases of the rails. Support for the members 14 is provided by pillars of concrete 24 or other suitable means upon which the strengthening ribs 22 rest.

105 It will now be seen that I have provided 110

an efficient means which may be quickly operated for the laying, removing and replacement of block pavements. In operation, the plates 4 are interposed between the 5 rails and are supported thereby, the ribs 7 resting upon the base of the rail at three points; the sand is then spread over the upper surface of the plate to a suitable thickness (although it will be understood that the 10 sand is not necessary to the successful use of my improvement) and the blocks 11 are then suitably disposed upon the top of the said member 4 and within the ribs 10 and the projecting members 13. The plates 14 extend 15 outside of the rail are then placed in position and the sand and paving blocks placed therein.

I have also provided means whereby the supporting plates and the pavement carried 20 thereby may be speedily removed when for any reason that is required in connection with the repair or replacement of the blocks, or the re-building or re-laying of the rails of the track. My improved means for this purpose 25 comprises a metal bar 25 having flanges 26 and 27 depending substantially three inches from the ends thereof, the length of the bar being substantially the distance between the centers of the heads of the rails 1 and 2 when positioned to form the track. Near one end 26 of the bar 25 I provide a hole 28, the end of the bar being slightly thickened at this point, through which passes the bolt 29 the screw threaded end of which passes 30 into the screw threaded opening 30 formed in the edge of the supporting plate 4. It will be understood that one or more of these lifting devices may be used as desired for each supporting plate and that a suitable 40 number of holes 30 may be correspondingly provided. The lifting device is utilized by placing the lower edge of the flange 27 upon the head of the rail 2 and the lower edge of the flange 26 upon the head of the rail 1. The screw threaded end of the bolt 29 is then caused to engage with the screw threaded opening 30 and the rotation of the bolt then causes the adjacent side of the supporting plate 4 to be lifted until it reaches a point above the head of the rail 1, thereby permitting this end of the plate to be grasped and lifted by any suitable means, manually or otherwise, and the entire plate and the paving blocks and sand carried 50 thereby to be removed. It will be readily understood that by removing the bolts 20 the supporting plates 14 on the outside of the

rails and the paving blocks and sand carried thereby may be lifted and removed manually or in any other suitable way. Access 60 is thereby gained to the rails for repair, re-building or replacement following the completion of which the supporting plates 4 and 14 may be quickly replaced.

It will be understood that variations and 65 changes in the details of construction, arrangement and location of parts will readily suggest themselves to persons skilled in the art and fall within the spirit and scope of my invention.

I do not desire therefore to be limited or restricted to the exact details of construction and arrangement shown and described.

Having thus described my invention, I claim and desire to protect by Letters Pat- 75 ent of the United States:

1. A pavement construction adapted for railway tracks comprising a metal plate of a width slightly less than the distance between the rails and removably positioned therebetween, paving material upon said plate, ribs extending longitudinally along the bottom of the plate and ribs extending transversely thereto, the ends of said last-mentioned ribs being adapted to fit the bases 80 of said rails and providing a support for said plate.

2. A pavement construction adapted for railway tracks comprising a plate removably positioned between the rails, a layer of sand 90 upon said plate, blocks of paving material upon said sand, said plate being provided with flanges extending along the sides thereof for retaining said blocks and said sand, and ribs extending across the bottom of said plate, the ends of said ribs being adapted to engage the bases of said rails and to provide support for said plate.

3. A pavement construction adapted for railway tracks comprising a plate removably 100 positioned between the rails, a layer of sand upon said plate, blocks of paving material upon said sand, said plate being provided with flanges extending along the sides thereof for retaining said blocks and said sand, 105 means projecting from the plate along the ends thereof for retaining said sand, ribs extending across the bottom of said plate, the ends of said ribs being adapted to engage the bases of said rails and to provide support for 110 said plate.

In witness whereof, I have hereunto set my hand this 6th day of December, 1922.

ANTHONY MANGANIELLO.
